ETIENNE FAJON.

UNITED STATES PATENT OFFICE.

ETIENNE FAJON, OF BOSTON, MASSACHUSETTS, ASSIGNOR TO THE ROXBURY CARPET COMPANY, OF SAME PLACE.

DESIGN FOR CARPET.

SPECIFICATION forming part of Design No. 13,845, dated October 24, 1882.

Application filed September 25, 1882. Term of patent 3½ years.

To all whom it may concern:

Be it known that I, ETIENNE FAJON, of Boston, in the county of Suffolk and State of Massachusetts, have invented a new and original 5 Design for Carpets, of which the following is a specification.

The nature of my design is fully shown in the accompanying photographic illustration.

The design is composed of the floral designs 10 or bouquets, scrolls, and variously-ornamented borders, and other figures, all as shown.

I claim—

The design for a carpet, substantially as shown and described.

In testimony whereof I have signed my name 15 to this specification, in the presence of two subscribing witnesses, this 23d day of September, 1882.
